UNITED STATES PATENT OFFICE

2,427,224

ROTARY HYDRAULIC PUMP

James E. Morton, Harvey, Ill.

Application August 3, 1944, Serial No. 547,882

8 Claims. (Cl. 103—161)

1

The invention relates to radial piston hydraulic pumps.

One object of the invention is to provide improved means for automatically shifting the ring for imparting inward strokes to radial pistons in the cylinders in the rotor, responsive to excessive pressures of the fluid.

Another object of the invention is to provide improved mechanical means and fluid pressure means for adjusting the ring for imparting radial movements to said pistons to vary the eccentricity of the ring and the volume of hydraulic fluid discharged by the pump.

Another object of the invention is to provide improved valve means for controlling the discharge of fluid under pressure from the pump casing.

A still further object of the invention is to provide a pump with a ring for imparting inward strokes to the radial pistons in the rotor which is provided with means for shifting the pistons outwardly when the pump is traveling at low speeds and centrifugal force is insufficient to impart outward strokes to the pistons.

Another object of the invention is to provide valve mechanism for conducting fluid to and from the radial cylinders in rotative succession in the rotor in which the off-center pressure between the rotor and the stationary valve member is balanced to reduce friction and to provide an improved balanced rotary valve around said stationary member for controlling the discharge of fluid from the pump casing.

Other objects of the invention will appear from the detailed description.

The invention consists in the several novel features hereinafter set forth and more particularly defined by claims at the conclusion hereof.

In the drawings:

Fig. 1 is a transverse section through the pump.

Fig. 2 is a section taken on line 2—2 of Fig. 1.

Fig. 3 is a plan.

Fig. 4 is a longitudinal section of the stationary valve member taken on line 4—4 of Fig. 6, associated parts being illustrated in dotted lines.

Fig. 5 is a section taken on line 5—5 of Fig. 2.

Fig. 6 is a section taken on line 6—6 of Fig. 2.

Fig. 7 is a section taken on line 7—7 of Fig. 2.

Fig. 8 is a section taken on line 8—8 of Fig. 2.

The invention is exemplified in a pump comprising a casing which may be stationarily or portably supported in any suitable manner. The casing comprises a cylindrical wall 10, a side wall 11, integral with the wall 10, and a removable head or side wall 12 which is secured by bolts 55

2

13 to wall 10. The rotor in the casing comprises a rotor-body 14 which is keyed at 15 to a sleeve 16 which is journaled in anti-friction bearings 17 which are supported respectively in side wall 11 and head 12 of the casing. The inner end of the sleeve 16 terminates at the inside of the side wall 11 of the casing and its outer end 18 extends through the head 12 and is splined as at 19 to a shaft 20 which may be driven in any suitable manner, usually by an electric motor.

A series of radial cylinders 21, the outer ends of which are open, are formed in the rotor-body 14. A piston 22 is slidable in each cylinder 21 and carries adjacent its outer end a cross-shaft 23 which extends through the piston and carries at each side of the rotor body a roller 24. The cylinders are provided with slots 25 in which bosses 26 on the piston are radially movable.

A ring 30 is supported for transverse sliding movement on guides 31 which are integrally formed with the rim of the casing to permit the ring to be shifted from a position in which it is coaxial with the rotor to an eccentric position. The inner cylindrical periphery 32 of ring

25 30 functions as a circular track engaged by the rollers 24 for imparting inward strokes to the piston for discharging fluid under pressure from the cylinders 21 in rotative succession, when the ring is eccentrically positioned relatively to the 30 rotor, and to permit the pistons to idle when the ring is positioned concentrically with the rotor. The ring 30 has affixed thereto inwardly extending flanges or sides 34 which engage abutments 35 on side wall 11 and head 12 to confine the 35 ring against axial movement in the casing. Each side 34 of ring 30 is provided with a circular inwardly facing groove 36 which is concentric with the circular track 32. Rollers 37 are carried by cross-shafts 23 at the sides of pistons 22 and the 40 outer ends of said shafts extend into the grooves 36. The pump in normal operation, shifts the pistons 22 at sufficiently high speed to cause centrifugal force to move the pistons outwardly for engagement of the rollers 24 with the circular track 32 in the ring 30 for inward movement of the pistons by the eccentric track 32. When the 45 rotor is driven at an insufficient speed to cause centrifugal force to move the pistons 22 outwardly, the inner sides of circular grooves 36 engaging the rollers 24 will shift the pistons 22 outwardly for drawing fluid into the inner ends of the cylinders. Sleeve 16 of the rotor is provided with radial ports 39 for the flow of fluid into and out of the cylinders in rotative succession.

A cup-shaped casing section 40 is secured by

bolts 41 to the side wall 11 of the casing. Pipes 42 and 43 are connected to the casing section 40 and function to deliver fluid to and from said casing section respectively. A stationary cylindrical valve member 44 has its outer end secured by screws 45 to the inner side of casing section 40 and extended into the sleeve 16 of the rotor for conducting fluid to and from the cylinders 21 successively in their rotation around said valve-member. The inner portion 46 of valve member 44 has a cylindrical periphery which fits in the sleeve 16 which rotates with the rotor and is provided with ducts for conducting fluid to and from the cylinders 21 in their rotative succession. The outer portion 47 of stationary valve member 44 is cylindrical and fits in the bore of a rotatable ring-valve 48 which fits in a cylindrical seat 49 in the casing-section 40. Stationary valve member 44 is provided with a pair of longitudinal ducts 50 which are communicatively connected by a duct 51 in said valve member with an arcuate duct 52 in the ring valve 48 for the flow of the fluid through longitudinal ducts 50 to a duct 54 with which the ports 53 in the sleeve 16 at the inner ends of cylinders 21 are adapted to communicate in rotative succession. The stationary valve member 44 is also provided with a pair of longitudinal cylindrical ducts 56 which are connected to a duct 57 for communication with the ports 53 in rotor sleeve 16 and to a port 59 which communicates with an arcuate port 60 in the ring valve 48. In the operation of the pump the fluid enters pipe 42, passes through port 52 in ring-valve 48, port 51, duct 56, port 54 in the stationary valve-member 44 and ports 53 in sleeve 16, to the cylinders 21, and is discharged from the cylinders in rotative succession from ports 53 in sleeve 16, port 51, longitudinal ducts 56 and port 59 in valve member 44, and port 60 in ring-valve 48 to the discharge pipe 43. The ring valve 48 controls the volume of fluid to and from the pump cylinders.

The periphery of the portion 46 of the stationary valve member 44 which fits in the sleeve 16 is provided with a pair of arcuate grooves 63 (Fig. 7) which are communicatively connected by ports 64 to one of the longitudinal ducts 50. The opposite side of said periphery is provided with a pair of arcuate grooves 65 which are communicatively connected by a port 66 with one of the longitudinal ducts 50. The portion 47 of the stationary valve member 44 which fits in the ring valve 48 is provided with a pair of arcuate grooves 67 which are communicatively connected by a port 68 with one of the ducts 50. The opposite side of said periphery is provided with a pair of arcuate grooves 69 which are communicatively connected by a port 70 to one of the longitudinal ducts 50. These arcuate grooves have a combined projected area equal to the larger port area on opposite side, and therefore equal fluid pressure on opposite sides to provide a perfect hydraulic balance or floating action of the rotor and the valve 48 around the stationary valve-member 44. The ring-valve is provided at its outer end with gear beveled teeth 72. A pinion 73 is fixed to a shaft 74 which is journaled in a bearing 65, meshes with teeth 72, for rotating valve 48 around valve-member 44. The outer end of shaft 74 is provided with a wheel 76 by which shaft 74 may be rotated.

The ring 30, which is provided with a circular track 32 for imparting inward strokes to the pistons 22, is adjustable transversely in the casing 75

for varying the length of the piston strokes for varying the volume of the fluid displaced by the pump and is movable into concentric relation with the rotor for confining the pistons 22 against movement in the cylinders 21. The means for controlling the position of ring 30 comprises a plunger 78 which is slidably mounted in the casing and engaged by a spring 79 which is confined in a cap 80 which is secured to the casing and engages a follower 81 which is adjustable by a screw 82 to vary the loading of the spring 79. This constitutes spring means for forcing ring 30 towards its eccentric position, which is yieldable to permit said ring to be shifted into concentricity with the rotor. Mechanical means is also provided at the opposite side of ring 30 for shifting the ring against the force of spring 79 for manually varying the eccentricity of the ring or shifting it into its concentric position. This means comprises a pair of pins 84 which are slidably mounted in the pump casing, and a cap 85, a cross-head 86 rigidly connected to the outer ends of pins 84, a wheel 87 fixed to a shaft 88 which is provided with a screw-thread 89 which extends through a female thread in the cross-head 86 and is provided at its inner end with a head 90 which is confined against axial movement by the cap 85 and a plate 91 which is secured to the outer face of said cap.

Fluid pressure operable means is also provided for shifting the ring 30 against the force of spring 79 toward its concentric position for varying the volume of the fluid displaced by the pump or shifting the ring 30 to its concentric position and causing the pistons to idle. This fluid pressure means comprises a piston 93 which is slidably mounted in a cylinder 94 in the cap 85 and has its inner end engaging the outer periphery of ring 30. A pipe 95 delivers fluid under pressure from one of the outlet ports 56 in valve member 44 into the cylinder 94 so that the piston 93 will be exposed to pressure proportionate to the pressure of the fluid in the discharge ducts 56. The spring 79 is loaded for the minimum working pressure, for example, 500 lbs. p. s. i. which can be varied by the set screw 82. The fluid pressure against piston 93 which varies responsively to variations in the fluid under pressure in the ducts 56 is normally less than the pressure applied to spring 79. In the event that the pump becomes overloaded by the machine driven by the pump, the fluid pressure in the ducts 56 and cylinder 94 becomes sufficient to automatically shift the ring 30 to decrease its eccentricity and vary the length of the piston strokes and thereby reduce the volume of fluid discharged from and the pressure of fluid in the pump. The eccentricity may be varied to vary the length of the piston strokes or the ring 30 may be forced into its concentric position by a predetermined increase in pressure so that the pistons will not be reciprocated. This exemplifies fluid pressure operable means for varying the length of or discontinuing the piston strokes responsively to excessive pressure resulting from overloading of the pump.

The operation of the pump will be as follows: When the drive shaft is driven, the rotor, including sleeve 16, rotor body 14 in which the cylinders 21 are formed, and the radial pistons will be driven to draw fluid into the cylinders in rotative succession from pipe 42 and to discharge the fluid through pipe 43. Fluid will be drawn by the outstrokes of the pistons 22 into the cylinders via port 52 in ring valve 48, ducts 56

and 50 in stationary valve member 44, arcuate ports 54 and the ports 38 in sleeve 16. Under normal speed centrifugal force will shift the pistons 22 outwardly while their rollers 24 engage the circular track 32 in ring 30, while the ring is eccentrically positioned around the roller. During low speeds when centrifugal force is insufficient to shift the piston outwardly, the inner sides of the grooves 36 in the sides of ring 30 will shift the pistons outwardly. The ring will impart, in rotative succession, inward strokes to the pistons 22 and force the fluid under pressure via ports 38 in sleeve 16, port 57, longitudinal ducts 56 and port 59 in stationary valve member 44, port 60 in ring valve 48 to the discharge pipe 43. During the operation of the pump the fluid delivered to the arcuate grooves 63 from the intake duct 50 and the fluid under pressure in the arcuate grooves 65 from duct 56 will balance the pressure between the stationary valve member and the rotor. The arcuate grooves 67 which are connected to fluid in one of the intake ports 50 and the pressure of the fluid in arcuate grooves 69 from one of the discharge ports 56 will balance the pressure between the ring valve 48 and the stationary valve member so that the ring valve can be freely operated. Normally, the ring 30 will be held at its point of greatest eccentricity for the maximum length of the piston strokes, and the force of spring 78 will be sufficient to hold said ring in such position. If at any time, the pressure in the discharge ducts in stationary valve member 44 becomes excessive through overloading of the pump, fluid under such pressure will flow from one of the ports 56 via pipe 85 into the cylinder 84 and force the piston 93 inwardly to move ring 30 against the force of the spring 78 on the opposite side of said ring, toward its concentric position around the rotor. As a result the ring 30 will be automatically shifted responsive to variations in the pressure of fluid in the discharge side of the pump, to reduce or stop the piston strokes. This fluid pressure operable means functions to relieve the pump and prevent damage to machinery driven by the pump, arising from excessive pressure. As soon as the pressure of the discharge fluid drops to working range, the spring 78, through plunger 78 will restore ring 30 to its normal eccentricity.

The invention exemplifies a rotary pump of the radial piston type which includes spring means for pressing the piston-shifting ring into its eccentric position; fluid pressure operable means for shifting said ring from its point of greatest eccentricity toward its concentric position against the force of the spring means; a ring valve around a stationary member for controlling the fluid to and from the pump; a stationary valve member which is provided with grooves for balancing the pressure between said member and the rotor and between said member and the ring valve; a ring for imparting strokes to the radial piston which comprises sides which rigidify the ring and are provided with means for imparting outward strokes to the radial moveable piston when the pump is driven at low speeds.

Having thus described the invention what I claim as new and desire to secure by Letters Patent is:

1. The combination with a rotary hydraulic pump comprising a rotor-body provided with radial cylinders, pistons slideable in the cylinders, a non-rotatable casing for the rotor, and means

for controlling the flow of fluid to the cylinders in rotative succession; of a ring slidably mounted for transverse movement and non-rotatably confined in the casing and provided with a circular track for imparting inward strokes to the pistons, of spring-means acting on one side of the ring to press it into a portion eccentric to the rotor, fluid-pressure operable means comprising a piston at the opposite side of the ring for shifting the ring toward its concentric position against the force of said spring-means, means for delivering fluid from the cylinder at discharge pressure to said fluid-pressure operable means, pins slideable in the casing for similarly shifting the ring, and screw-means for shifting said pins independently of said fluid pressure operable means.

2. The combination in a rotary hydraulic pump of a casing provided with an inlet and outlet for fluid, a driven rotor-body in the casing provided with radial cylinders, an eccentric ring non-rotatably mounted in the casing provided with a track for imparting inward strokes to the pistons, a stationary valve member provided with ducts for conducting fluid to and from the cylinders in rotative succession, and a rotary valve around said stationary valve member and in the casing, for controlling the outflow of fluid from said valve member to said outlet.

3. The combination in a rotary hydraulic pump of a casing provided with an inlet and outlet for fluid, a driven rotor-body in the casing provided with radial cylinders, an eccentric ring non-rotatably mounted in the casing provided with a track for imparting inward strokes to the pistons, a stationary valve-member provided with ducts for conducting fluid to and from the cylinders in rotative succession, and a ring valve rotatable around said stationary valve member and in the casing, for controlling the outflow of fluid from said valve-member to said outlet.

4. The combination in a rotary hydraulic pump of a casing provided with an inlet and outlet for fluid, a driven rotor-body in the casing provided with radial cylinders, an eccentric ring non-rotatably mounted in the casing provided with a track for imparting inward strokes to the pistons, a stationary valve-member provided with ducts for conducting fluid to and from the cylinders in rotative succession, a ring-valve rotatable around said stationary valve-member and in the casing, for controlling the outflow of fluid from said valve-member to said outlet, and means between the valve-member and the ring-valve for balancing the pressure around the ring-valve.

5. The combination in a rotary hydraulic pump of a casing provided with an inlet and an outlet for the fluid, a driven rotor-body in the casing provided with radial cylinders, pistons slideable in the cylinders, an eccentric ring, non-rotatably mounted in the casing, provided with a track for imparting inward strokes to the piston, a valve-member stationarily secured in the casing extending into the rotor and provided with ducts for conducting fluid to and from the cylinders in rotative succession, and means between said rotor-body and said stationary member for balancing the pressure of the fluid on the rotor-body.

6. The combination in a rotary hydraulic pump of a casing provided with an inlet and an outlet for the fluid, a driven rotor in the casing provided with radial cylinders, pistons slideable in the cylinders, an eccentric ring, non-rotatably mounted in the casing, provided with a track for imparting inward strokes to the piston, a valve-member

stationarily secured in the casing extending into the rotor and provided with ducts for conducting fluid to and from the cylinders in rotative succession, means between the rotor-body and said member for balancing the pressure on the rotor, a valve around said stationary member for controlling the outflow of fluid from said member to the outlet, and means between said valve and said stationary member for balancing the pressure of the fluid on the valve.

7. The combination in rotary hydraulic pump, of a casing including sides; a rotor body in the casing provided with radial cylinders; pistons slideable in the cylinders, means for controlling the flow of fluid in rotative succession to and from the cylinders, an eccentric ring non-rotatably and slidably mounted in the casing and provided with a track for imparting inward strokes to the pistons, flanges rigidly secured to and extending inwardly at the sides of the eccentric ring and having outer faces abutting the inner sides of the casing for holding the eccentric ring against axial movement, cross-shafts carried by the pistons, and rollers carried by the cross-shafts at the sides of the pistons and engaging the track on the eccentric ring, said flanges being provided with tracks engageable by the ends of the cross-shafts for shifting the pistons outwardly when centrifugal force is insufficient to move them outwardly.

8. The combination in a rotary hydraulic pump, of a casing including sides; a rotor body in the casing provided with radial cylinders; pistons slideable in the cylinders, means for controlling

the flow of fluid in rotative succession to and from the cylinders, an eccentric ring non-rotatably and slidably mounted in the casing and provided with a track for imparting inward strokes to the pistons, flanges rigidly secured to and extending inwardly at the sides of the eccentric ring and having outer faces abutting the inner sides of the casing for holding the eccentric ring against axial movement, a circular track on the eccentric ring for imparting inward strokes to the pistons, cross-shafts carried by the pistons, and rollers carried by the cross-shafts and engaging the track on the eccentric ring for imparting inward strokes to the pistons, said flanges being provided with grooves into which the ends of the cross-shafts extend, for shifting the pistons outwardly when centrifugal force is sufficient to move them outwardly.
